UNITED STATES PATENT OFFICE.

GEORGE W. PEASE, OF PITTSFIELD, MASSACHUSETTS.

GARMENT.

1,272,706.

Specification of Letters Patent. Patented July 16, 1918.

Application filed August 7, 1917. Serial No. 184,837.

To all whom it may concern:

Be it known that I, GEORGE W. PEASE, a citizen of the United States, and a resident of Pittsfield, county of Berkshire, State 5 of Massachusetts, have invented a new and useful Garment, of which the following is a specification.

My invention relates to union garments such as overalls, pajamas, or the like, and 10 has for its object to produce such a garment which will give to the movements of the body of the wearer without unduly straining the garment.

A further object is to produce a union 15 garment wherein dust and dirt will be excluded from within the same.

A further object is to produce elastic means for holding the garment in position, and to provide means for ready access to 20 the elastic means from the outside.

These and further objects will more fully appear in the following specification and accompanying drawings, considered together or separately. I have illustrated one embodiment of my invention in the accompanying drawings in which like parts in all of 25 the figures are designated by similar reference characters, and in which—

Figure 1 is a back view of a garment embodying my invention.

Fig. 2 is an elevation, on an enlarged scale, of the invention viewed from the inside.

Fig. 3 is a section, on an enlarged scale, on the line 3—3 of Fig. 1.

Fig. 4 is a similar view on the line 4—4 of Fig. 1.

Fig. 5 is a similar view on the line 5—5 of Fig. 1, and

Fig. 6 is a view similar to Fig. 2 of a modification.

My invention relates to a union garment of the same general type as shown in my co-pending application for patent filed June 13, 1916, and numbered serially 103,371, 45 which is provided with an opening extending down the front from the collar to the crotch to permit donning and removing the garment.

In carrying out my invention I provide a 50 garment comprising a body portion 1 and a trousers portion 2 secured together except for a very short distance at the back of the garment at approximately the waist line thus producing a short horizontal slit 3. A 55 patch 4 of material similar to that of which the garment is made is secured to the inside

of the back of the garment above the slit 3 by a row of stitching 5 at each side of the patch vertically upward from each side of the slit. This patch produces a pocket 60 open at the bottom from the outside of the garment, and open at the top from the inside. By means of the slit and patch the hand may be passed through the slit at the waist line and into the garment over the 65 upper edge of the patch 4. The patch may be an integral part of the trousers as shown in the drawings or it may be a separate piece of material stitched to the trousers at that portion of the trousers which is not 70 to be attached to the coat portion.

A suspender comprising an elastic member 6 is secured to the body portion 1 in the vertical center of the back thereof and above the patch 4. The elastic member is secured 75 to a tab 7 by means of a buckle or other suitable fastening means 8 so that the suspender may be readily removed during laundering the garment. The suspender carries the usual adjustable support 9 which carries 80 looped runners 10, the loops on the ends of which engage buttons 11 secured to the patch 4 between the same and the back of the body portion.

The patch extending as it does a considerable distance above the slit, will prevent exposure of the clothing worn inside the garment no matter how far the garment may be opened at the slit, and will also close the slit to such an extent as to virtually exclude dust and dirt.

When it is desired to fasten or unfasten the loop of the runner to or from the button 11 when the garment is being worn, the hand may be passed upward through the slit and 90 the loops readily attached or detached to or from the buttons.

In order to prevent displacement of the free end of the suspender and that the loops of the runner may always be in position to 100 be reached through the slit 3, I provide a keeper 12 in the form of a strip or suitable material which may be stitched or otherwise secured to the inside of the back of the body portion 1 directly above the top edge of the patch 4. The keeper is preferably stitched to the body portion at each side of the center line, leaving an unsupported portion in vertical alignment with the suspender and with the center line between the buttons 110 11, 11.

The lower end of the suspender carrying

the runner 10 will pass between the unsupported portion of the keeper and the back of the body portion, and as the lower edge of the keeper is in close proximity to the free upper edge of the patch 4 the loops cannot swing away from the center line of the back of the garment but will always be held in position to be grasped by the hand and engaged to the buttons 11.

10. In the modification shown in Fig. 6 the patch 4 is extended upward and stitched to the back of the garment inward from its vertical edges toward the center, but leaving an unsupported portion at the center 15 through which the lower end of the suspender may pass.

While I have termed the portion 4 a patch, it is obvious that it may be an integral part of the trousers or of the body portion. In 20 order to prevent the garment from gapping at the slit when the suspender is detached from the buttons and cause the edges of the slit to resume their normal positions after they have been moved apart by the bending 25 of the body of the wearer, I provide a stiffening stay 13 attached to the inside of the trousers portion and extending to the top of the patch 4, and a similar stay 14 extending from the tab 7 to the upper edge of 30 the slit 3. The stays 13 and 14 may be of any suitable material and may be secured to the garment in any desired manner.

It will be understood that instead of making the upper or coat portion 1 separate from 35 the trousers 2 and then sewing them together except for a short distance at the back the two portions may be made of a single piece of material, in which event the patch must be a separate piece sewed on below the slit.

The operation of my invention is obvious from the above description.

In accordance with the provisions of the 45 patent statutes, I have described the principle of my invention, together with the apparatus which I now consider to represent the best embodiment thereof, but I desire to have it understood that the apparatus shown is merely illustrative, and that the invention 50 may be carried out in other ways.

Having thus described my invention what I now claim as new and desire to secure by Letters Patent, is—

1. A union garment comprising a body 55 portion and a trousers portion permanently secured together at the back and front, there being a substantially horizontal slit at the back of the garment, the length of said slit being less than the distance across the back 60 of the garment, a member attached to the trousers portion and extending upward inside of the body portion, means for securing said member to the body portion at a point distant from the slit, an elastic element 65 attached to the inside of the body portion

above the member and means for attaching the element to the member above the slit.

2. A union garment comprising a body portion and a trousers portion permanently secured together at the front and the back, 70 there being a slit at the back in proximity to the waist line, a member secured to the inside of the back of the garment, a portion of said member being unattached to the garment, a suspender attached to the inside of 75 the back of the garment in vertical alinement with the member, fastening means carried by the member and being located between the member and the back of the garment, the free end of the suspender extending between the back of the garment and the member and removably attached to the latter, said slit permitting access to the suspender from the outside of the garment at the back.

3. A union garment comprising a body portion and a trousers portion permanently secured together at the front and the back, 80 there being a slit at the back in proximity to the waist line, a member secured to the inside 85 of the back of the garment, a portion of said member being unattached to the garment, a suspender attached to the inside of the back of the garment in vertical alinement with the member, fastening means carried by the member and being located between the member and the back of the garment, the free end of the suspender extending between the back of the garment and the member and removably attached to the latter, said slit permitting access to the suspender from the outside of the garment at the back, and a stiffening stay carried by the 90 back of the body portion and extending upward from the upper edge of the slit.

4. A union garment comprising a body portion and a trousers portion secured together at the front and the back, a member secured to the inside of the back of the garment, a portion of said member being unattached to the garment, a suspender attached to the inside of the back of the garment in vertical alinement with the member, fastening means carried by the member and being located between the member and the back 110 of the garment, the free end of the suspender extending between the back of the garment and the member and removably attached to the latter, there being a slit in the garment to permit access to suspender from the outside of the garment at the back, and a stiffening stay carried by the back of the trousers portion and extending upward to the upper edge of the member.

5. A union garment comprising a body portion and a trousers portion secured together at the front and the back, a member secured to the inside of the back of the garment, a portion of said member being unattached to the garment, a suspender at- 125

tached to the inside of the back of the garment in vertical alinement with the member, fastening means carried by the member and being located between the member and the 5 back of the garment, the free end of the suspender extending between the back of the garment and the member and removably attached to the latter, there being a slit in the garment to permit access to suspender 10 from the outside of the garment at the back, a stiffening stay carried by the back of the trousers portion and extending upward to the upper edge of the member, and a stiffening stay carried by the back of the body 15 portion and extending upward from the upper edge of the slit.

6. A union garment comprising a body portion and a trousers portion permanently secured together at the front and back, there 20 being a slit in the back of the garment at approximately the waist line, a member secured to the inside of the garment below the slit and extending upward, the upper edge of the member being unattached, a suspender 25 removably attached to the inside of the body portion vertically above the member, the lower free end of the suspender extend-

ing between the member and the back of the garment, and a keeper extending horizontally across the back of the garment and retaining the suspender between the keeper and the back of the garment, said keeper being attached to the garment at the sides of the suspender whereby said suspender will be retained in alinement with said slit. 30 35

7. A union garment comprising a body portion and a trousers portion permanently united at the back and front, there being a slit in the back of the garment, a member secured to the inside of the back of the 40 garment and covering the slit, a portion of the member being unattached to the garment, a suspender attached to the back of the garment in vertical alinement with the member, and fastening means whereby the 45 free end of the suspender may be secured to the member.

This specification signed and witnessed this 30th day of July, 1917.
